ACTUATOR CAP FOR A PRESSURIZED CONTAINER

Thomas H. Hayes, Westport, Conn., assignor to
VCA Corporation, Greenwich, Conn.

Filed Apr. 24, 1972, Ser. No. 247,225

Term of patent 14 years

Int. Cl. D9—01

U.S. Cl. D9—258

Fig. 1

Fig. 2

Fig. 3

Fig. 4

Fig. 5

FIG. 1 is a front elevational view of an actuator cap for a pressurized container, showing my new design.

FIG. 2 is a right side elevational view.

FIG. 3 is a rear elevational view.

FIG. 4 is a top plan view, and

FIG. 5 is a bottom plan view.

I claim:

The ornamental design for an actuator cap for a pressurized container, as illustrated and described.
